UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING APPARATUS

Application filed December 12, 1924, Serial No. 755,484. Renewed November 8, 1928.

My invention relates to mining apparatus. An object of my invention is to provide an improved mining apparatus. Another object of my invention is to provide an improved mining apparatus of the wheel mounted type wherein the mining machine is adapted to cut from the tracks. Still another object of my invention is to provide an improved shearing machine adapted to cut kerfs in a vertical plane in the face of the coal. Still another object of my invention is to provide an improved wheel mounted shearing machine of the pivoted bar type having improved means for swinging the cutter bar and improved means for holding the cutter bar in its adjusted positions. A still further object of my invention is to provide an improved shearing machine of the self-propelled truck mounted type wherein improved means are provided for propelling the truck during the cutting and transport operations. Still another object of my invention is to provide an improved mining machine of the pivoted bar type having an improved bar swinging mechanism. These and other objects and advantages of my invention will, however, hereinafter more fully appear.

In the accompanying drawings I have shown for purposes of illustration one form which my invention may assume in practice.

In these drawings,—

Fig. 1 is a side elevation of the complete shearing machine, parts being broken away to facilitate illustration.

Fig. 2 is a plan view of the machine shown in Fig. 1.

Fig. 3 is a transverse horizontal sectional view taken substantially on line 3—3 of Fig. 1, parts being omitted to facilitate illustration.

Fig. 4 is a developed sectional view taken substantially on line 4—4 of Fig. 1.

Fig. 5 is a diagrammatic view illustrating the operation of the machine during cutting.

In this illustrated form of my invention I have shown a truck frame 1 mounted on wheels 2 adapted to move relative to a track way 3. The truck frame 1 has fixed thereupon a unitary mining machine, generally designated 4, herein of the so called longwall

type normally slidable on its own bottom on the mine and having a generally rectangular machine frame 5 disposed on its edge or side on a horizontal plane surface as at 6, on the truck frame. Further, the machine is provided with an elongated cutter bar 7 having the usual cutter bit carrying cutter chain 8 which is adapted to be circulated about the cutter bar by means of a usual drive sprocket 8', the bar being pivoted, as at 9, on a transverse horizontal axis on the front end of the machine frame 5 in a well known manner. A usual electric cable reel 10 is suitably supported on the rear end of the truck frame 1 and power medium is transmitted by means of conducting cables 11 and 12 leading to the reel and the mining machine driving motor (not shown) respectively. The machine driving motor is herein of the usual electric reversible type and by it the usual driving connections for the cutter chain, the improved means for swinging the bar about its pivot, and improved means for driving the truck wheels, are driven as hereinafter more fully described.

In describing my improved mechanism it will herein be observed that the rear end of the horizontally disposed longitudinally extending armature shaft 13 of the driving motor has secured thereto an armature pinion 14 (see Fig. 3) which meshes with a spur gear 15 rotatable on a parallel axis disposed in the same horizontal plane as the axis of the pinion 14. As shown, this gear 15, in turn, has secured thereto a bevel pinion 16 which meshes with a bevel gear 17 rotatable in a vertical plane and this gear 17 is suitably secured by a key to a transversely disposed horizontal driving shaft 18. The shaft 18 is also adapted to drive suitable gearing substantially similar to that described in my prior Patent No. 1,470,570, Oct. 9, 1923, and which includes a suitable friction clutch (not shown) and a spur gear 19 suitably secured to a sleeve 20 journaled upon a transverse horizontal stud 21 disposed parallel with the shaft 18 and in the rear thereof. The sleeve 20 has formed thereon a chain feed sprocket 22 rotatable in a vertical plane and which is adapted to be driven at a fast speed in one

direction or at a slow speed in an opposite direction under the control of a suitable lever 22' and other control means, not shown, in the usual manner as clearly described in the 5 above mentioned patent. The sprocket is adapted to cooperate with an endless flexible feed or drive chain 23. Suitable guide sheaves or sprockets 24, 25, and 26 are herein provided which are rotatable on spaced horizontal axes parallel with the axis of the sprocket 22 and by these sprockets the chain 23 is guided relative to the drive sprocket 22. As illustrated, the chain 23 is adapted to pass upwardly from the sprocket 22 and 10 rearwardly around the guide sheave 24 and forwardly around a guide roll 27 rotatable on a vertical axis, as at 28, and supported by a suitable bracket 29 secured to the side of the machine frame 5, the chain passing from 15 this guide roll 27 rearwardly around and beneath a guide roll 30 rotatable on a horizontally disposed stud 31 carried by a longitudinally adjustable bracket 32. The bracket 32 is adapted to adjust the tension of the chain 23 and is held in its adjusted position by 20 means of a plurality of bolts 33 cooperating with the machine frame. The chain then passes forwardly from the bottom of the guide roll 30 and around a chain sprocket or 25 sheave 34 rotatable on a horizontally disposed pin 35 carried by a radially extending arm 36 formed on integral members 37 and 38, rigidly secured as by bolts 39 and 40, respectively, to the cutter bar 7 (see Fig. 4). The chain 23 then passes 30 rearwardly around a driving sprocket 41 journaled coaxially with the shaft 18 and adapted to be driven from the drive sprocket 22 in an improved manner to be herein-inafter described. The chain 23 then passes 35 from beneath the sprocket 41 forwardly around a guide sprocket 42, similar to the sprocket 34, rotatable on a horizontally disposed pin 43 likewise carried by an arm formed on the members 37 and 38 and dia- 40 metrically disposed with respect to the pin 35 and the bar pivot 9, and then passes rearwardly around a longitudinally adjustable guide and tension adjusting roll 44, similar to the guide roll 30 and similarly mounted 45 with respect to the machine frame 1 but at the opposite edge thereof. A guide roll 45 disposed on an axis coaxial with the axis of the guide roll 27 but disposed at the opposite side of the machine frame is provided for 50 guiding the chain 23 rearwardly and around the guide sheaves 26 and 25 on the rear end of the machine frame 5 and to the lower side of the driving sprocket 22. When the driving sprocket 22 is driven in a counter-clock wise direction the cutter bar 7 is swung upwardly about its pivot 9 at a fast speed and when the direction of the driving sprocket 22 is reversed the cutter bar is swung downwardly at a slow or cutting speed, the swing- 55 ing movement of the bar being effected by

means of the endless chain 23 and suitable connections hereinafter described.

The shaft 18 is provided with a reduced portion 46 projecting laterally from the machine frame 5 (see Fig. 3) and this portion of the shaft has secured thereto, as by a key 47, an annular member 48 having suitable jaw clutch teeth 49. The chain sprocket 41 is likewise provided with jaw clutch teeth 50 oppositely disposed from the jaw clutch teeth 49. Journaled on a sleeve 50' on the portion 46 of the shaft 18 and interposed between the members 48 and 41 is a chain sprocket 51 secured, as at 52, to oppositely disposed sleeves 53 and 54. Moreover, the sleeves 53 and 54 are provided with suitable jaw clutch teeth adapted to selectively cooperate with the teeth 50 and 49 formed on the sprocket 41 and the member 48, respectively, in an improved manner. A chain 55 cooperates with the sprocket 51 and a similar sprocket 56 suitably secured to a transverse truck driving shaft 57 suitably carried by the truck frame 1 at the rear of the machine frame 5. The sprocket 56 is adapted to drive through a suitable friction clutch, generally designated 58, adapted to be operated by means of a suitable lever 59, a sprocket 60 which in turn drives, through chain and sprocket connections 61 and 62, the truck wheels. A belt connection 10' is connected 60 between the casing of the clutch 58 and a pulley secured to the reel 10 constituting a drive for the latter during truck movement.

It will herein be observed that a shipper member 63 cooperates with the sleeves 53 and 54 and this shipper member is suitably secured to a horizontally disposed non-rotatable operating shaft or rod 64 slidable on a combined bracket and chain guard 65 suitably secured to the side of the mining machine 4. It will herein be noted that the guard member 65 is provided with projecting lugs carrying set screws 65' which are adapted to engage the brackets carrying the sheaves 30 and 44 to adjust the latter to vary the tension of the chain 23. As illustrated, the outer end of the non-rotatable shaft or rod 64 is provided with a suitable grasping handle 66 which is adapted to be held in a plurality of operative positions by means of a spring pressed plunger 67 cooperating with spaced apertures 68 formed in a portion of the bracket 65. By throwing the clutch shipper 63 and consequently the teeth formed on the sleeve 53 into engagement with the teeth 50 formed on the chain sprocket 41, the sprocket 51 and hence the truck wheels 2 are driven by means of the chain 23 and the drive sprocket 22 at a slow speed in one direction and at a fast speed in the opposite direction. Further, by throwing the shipper 63 in an opposite direction, and consequently the teeth formed on the sleeve 54 into engagement with the teeth 49 formed on the member 48, the sprocket 51 and consequently the truck wheels 2 may be driv- 100 105 110 115 120 125 130

en directly from the shaft 18 at a fast speed.

The bar swinging members 37 and 38 secured to the cutter bar are provided with a cylindrical surface 69 with which a brake band 70 is adapted to cooperate to hold the bar in its different angular positions and this band is operated by means of a suitable link connection 71 and a lever 72 pivoted at 73 on the machine frame 5. A suitable rack 74 is provided for holding the lever 72 in its adjusted position.

It will herein be noted that the rear axle of the truck has secured thereto a suitable friction braking device, generally designated 75, (see Fig. 2) which is adapted to be operated through suitable connections 76 and 77 by means of a lever 78 pivoted in a suitable manner upon the truck frame 1. This braking device 75 is adapted to control the movement of the machine at certain times during the cutting operation and movement of the machine relative to a trackway of a steep gradient, consequently preventing an excessive rate of movement thereof. It will further be noted that the forward axle of the truck is provided with a suitable chain sprocket 79 with which a section of a chain 80 is adapted to cooperate, the free end of the chain being secured, as by a roof jack 81 (see Fig. 1). When the machine is moving relative to an inclined trackway the chain 80 is reeved about the sprocket 79 and in case the wheels lose their traction the machine is none the less fed.

In the operation of my improved shearing machine it will herein be noted that when the machine is moving about the mine at a fast or transport speed, the sprocket 51 is in driving relation with the sleeve 48 secured to the shaft 18 and the truck wheel drive is effected under the control of the friction clutch 58. When the machine is disposed adjacent the coal face, the driving sprocket 51 for the truck wheels is engaged with the sprocket 41 and the clutch 58 is thrown in and the brake 75 is set, preventing movement of the truck wheels and consequently preventing rotation of the sprocket 41. The driving sprocket 22 is then rotated at a fast speed in a counter-clockwise direction under the control of the lever 22 drawing in the chain between the sprocket 22 and the sprocket 41, which is prevented from rotating, and the cutter bar is swung upwardly, by the pull of the chain on the sprocket 34 carried by the cutter bar, from the full line position shown in Fig. 1 to the full line position, as at A, as shown in Fig. 5, the brake band 70 being released at this time. The brake band 70 is then again set, holding the bar in this position and the sprocket 22 is again driven, causing the chain 23 to drive the sprocket 41 to effect sumping. The sprocket 51 being in driving engagement with the sprocket 41, the truck wheels are hence driven under the control of a friction clutch

58 and the bar fed or dumped into the coal to the position indicated at B in Fig. 5. The brake band 70 is then released, the brake 75 set, preventing rotation of the sprocket 41 and the bar is swung downwardly, by the pull of the chain 23 on the sprocket 42, carried by the cutter bar, from the position B in Fig. 5 to the lower dotted line position C at a slow or cutting speed likewise driven from the sprocket 22 which then rotates in an opposite direction. The brake band 70 is then set and the drive sprocket 22 is rotated in the same direction as during the swinging cut. The sprocket being still in operative engagement with the drive sprocket 41, the cutter bar is withdrawn from the face of the coal to the position indicated at D in Fig. 5. The cutter bar is then swung upwardly to the full line position shown in Fig. 1 and the truck is driven rearwardly at a fast speed relative to the trackway, the cable reel 10 winding in the cable 11 at this time, in the usual manner.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining apparatus, a truck having running gear, a mining machine thereon having a cutter bar movable relative thereto, and means for driving the running gear of said truck and for moving said cutter bar relative to the truck including a flexible element common to both functions and means for effecting circulation thereof as a whole or movement of portions thereof relative to another fixed portion including means for holding a portion thereof stationary.

2. In a mining apparatus, a truck having running gear, a mining machine thereon having a pivoted cutter bar, and means for driving the running gear of said truck and for swinging said cutter bar including a flexible element common to both functions and means for effecting circulation of said element as a whole or movement of portions thereof relative to a fixed portion including means for holding a portion thereof stationary.

3. In a mining apparatus, a truck having running gear, a mining machine thereon having a cutter bar pivoted for movement in a vertical plane, and means for driving the running gear of said truck and for swinging said cutter bar including a flexible element common to both functions and means for effecting circulation of said element as a whole or movement of portions thereof relative to a fixed portion including means for holding a portion thereof stationary.

4. In a mining apparatus, a truck having

running gear, cutting mechanism movably mounted on said truck, and means for driving the running gear of said truck and for moving said cutting mechanism relative to the truck including a flexible element common to both functions and means for effecting circulation thereof as a whole or movement of portions thereof relative to another fixed portion including means for holding a portion thereof stationary.

5. In a mining apparatus, a truck having running gear, a mining machine thereon having a cutter bar movable relative thereto, and means for driving the running gear of said truck and for moving said cutter bar relative to the truck positively in opposite directions including a flexible transmission element and separate members engaging said flexible element, one of said members constituting a driving member for said running gear and the other member constituting a driving member for moving said cutter bar.

6. In a mining apparatus, a truck having running gear, a mining machine thereon having a pivoted cutter bar, and means for driving the running gear of said truck and for swinging said cutter bar positively in opposite directions including a flexible transmission element and separate members engaging said flexible element, one of said members constituting a driving member for said running gear and the other member constituting a driving member for moving said cutter bar.

7. In a mining apparatus, a truck having running gear, a mining machine thereon having a cutter bar pivoted for movement in a vertical plane, and means for driving the running gear of said truck and for swinging said cutter bar positively in opposite directions including a flexible transmission element and separate members engaging said flexible element, one of said members constituting a driving member for said running gear and the other member constituting a driving member for moving said cutter bar.

8. In a mining apparatus, a truck having running gear, cutting mechanism movably mounted on said truck, and means for driving the running gear of said truck and for moving said cutting mechanism relative to the truck positively in opposite directions including a flexible transmission element and separate members engaging said flexible element, one of said members constituting a driving member for said running gear and the other member constituting a driving member for moving said cutter bar.

9. In a mining apparatus, a truck having running gear, cutting mechanism movably mounted on said truck, and means for moving said truck and for moving said cutting mechanism positively in opposite directions including a common endless flexible element operatively connected to said cutting mechanism and said running gear at spaced points

along its length, and means for applying power to said flexible element.

10. In a mining apparatus, a truck having running gear, cutting mechanism pivotally mounted on said truck, and means for moving said truck and for swinging said cutting mechanism positively in opposite directions including a common endless flexible element operatively connected to said cutting mechanism and said running gear at spaced points along its length, and means for applying power to said flexible element.

11. In a mining apparatus, a truck having running gear, cutting mechanism movably mounted on said truck for pivoting about a horizontal axis, and means for moving said truck and for swinging said cutting mechanism positively in opposite directions including a common endless flexible element operatively connected to said cutting mechanism and said running gear at spaced points along its length, and means for applying power to said flexible element.

12. In a mining apparatus, a truck having running gear, cutting mechanism movably mounted on said truck, and means for moving said truck and for moving said cutting mechanism relative to said truck positively in opposite directions including a common endless flexible element and a plurality of selectively effective power elements cooperating directly therewith.

13. In a mining apparatus, a truck having running gear, cutting mechanism pivotally mounted on said truck, and means for moving said truck and for swinging said cutting mechanism positively in opposite directions including a common endless flexible element and a plurality of selectively effective power elements cooperating directly therewith.

14. In a mining apparatus, a truck having running gear, cutting mechanism movably mounted on said truck for pivoting about a horizontal axis, and means for moving said truck and for swinging said cutting mechanism positively in opposite directions including a common endless flexible element and a plurality of selectively effective power elements cooperating directly therewith.

15. In a mining apparatus, a wheeled truck, a mining machine mounted thereon having a pivoted cutter bar, and means for swinging said bar about its pivot and for driving said truck at a slow or fast speed including a plurality of selectively effective feeding members and a single flexible member cooperating directly therewith and transmitting power to drive the truck and to swing the bar.

16. In a mining apparatus, a wheeled truck, a mining machine mounted thereon having a cutter bar movable in a vertical plane, means positively for moving said cutter bar in opposite directions including a final flexible transmission element, and means asso-

- ciated with said moving means driven directly by said transmission element for driving the wheels of said truck.
17. In a mining apparatus, cutting mechanism movable in a vertical plane, and means for moving said cutting mechanism including a plurality of sprockets, a flexible member cooperating constantly with said sprockets, and means for holding one of said sprockets stationary while the other draws in said flexible member. 70
18. In a mining apparatus, a wheeled truck, a mining machine mounted on said truck having a cutter bar movable in a vertical plane, and means including a flexible transmission element for driving the wheels of said truck and for positively moving said cutter bar in opposite directions, and separate members directly engaging said flexible element, one of said members constituting a driving member for the truck wheels while the other member constitutes a driving member for moving said cutter bar. 80
19. In a mining apparatus, a truck, a mining machine mounted thereon provided with a cutter bar movable in a vertical plane, and means to move said bar positively in opposite directions and drive said truck including an endless flexible member cooperating therewith at spaced points along its length, and means for applying power to said flexible member. 85
20. In a mining apparatus, a truck, a mining machine mounted thereon having a cutter bar movable in a vertical plane, and means for moving said bar oppositely by power including a driving element carried by said mining machine rotatable in a vertical plane and an endless flexible member cooperating therewith, a portion of said flexible member being stationary during movement of said bar while another portion thereof is actuated by said driving element. 90
21. In a mining apparatus, a truck, a mining machine mounted thereon having a cutter bar movable in a vertical plane, and means for moving said bar and driving said truck including a plurality of selectively effective driving members and a common flexible member cooperating directly therewith to effect bar movement or truck drive selectively. 95
22. In a mining apparatus, a wheeled truck, a mining machine mounted thereon having a cutter bar movable relative to the truck in a vertical plane, and means for driving said truck at a plurality of speeds including a flexible element operatively connected with said cutter bar and means cooperating with said element to cause it to effect bar movement relative to the truck including means for holding a portion of said element stationary. 100
23. In a mining apparatus, a wheeled truck, a mining machine mounted thereon having a cutter bar movable in a vertical plane, means for driving said truck at a plurality of speeds including a flexible transmission element operatively connected with said cutter bar and said truck wheel driving means at different points along its length and operative to swing said bar in its plane, and means for applying power to said flexible element including a manually operable friction clutch. 105
24. In a mining apparatus, a wheeled truck, a mining machine thereon having a movable cutter bar, means for driving the wheels of said truck and for moving said bar in opposite directions by power including a common flexible transmission element, separate members engaging said flexible element, one of said members constituting a truck wheel driving member while said other member constitutes a driving member for moving said cutter bar, and means for varying the tension of said element. 110
25. In a mining apparatus, a wheeled truck, a mining machine thereon having a movable cutter bar, means for driving the wheels of said truck and for moving said bar positively in opposite directions including a common flexible element and separate members engaging said flexible element, one of said members constituting a truck wheel driving member while said other member constitutes a driving member for moving said cutter bar, and means including an adjustable guiding member for varying the tension of said element. 115
26. In a mining apparatus, a wheeled truck, a mining machine thereon having a movable cutter bar, means for driving the wheels of said truck and for moving said bar positively in opposite directions including a common flexible element, and means including a plurality of longitudinally adjustable guiding members for varying the tension of said element. 120
27. In a mining apparatus, a wheeled truck, a mining machine mounted thereon having a driving motor and a cutter bar movable in a vertical plane, and transmission means driven by said motor constantly cooperating with said bar and connectible at will with the truck wheels for swinging said bar in either direction in its plane and propelling said truck in opposite directions, said truck wheels being driven by the final transmission element of said bar swinging means. 125
28. In a mining apparatus, a wheeled truck, a mining machine mounted thereon having a driving motor and a cutter bar movable in a vertical plane, and transmission means driven by said motor constantly cooperating with said bar and connectible at will with the truck wheels for swinging said bar in either direction in its plane propelling said truck in opposite directions, said transmission means including a plurality of independently operable friction devices, one of which controls 130

both said truck wheel driving means and said bar swinging means.

29. In a mining apparatus, a wheeled truck, a mining machine of the type normally operative to cut when sliding on its bottom over a mine bottom resting edgewise thereon and secured thereto having a cutter bar movable in a vertical plane, and means constantly cooperating with said bar for moving the same in opposite directions.

30. In a mining apparatus, a wheeled truck, a mining machine of the type normally operative to cut when sliding on its bottom over a mine bottom resting on its edge thereon having a pivoted cutter bar movable in a vertical plane, and means constantly cooperating with said cutter bar for swinging the same about its pivot in opposite directions.

31. In a mining machine, a wheeled truck movable over a track way, a mining machine of the type normally operative to cut when sliding on its bottom over a mine bottom supported edgewise thereon and secured thereto comprising feeding and cutting mechanisms, the latter including a forwardly extending cutter bar, means supported by said truck and forming a transversely disposed pivot relative to which the bar is movable in a vertical plane, operative connections constantly engaged with said bar for moving the same about its pivot in either direction, and truck wheel driving mechanism cooperating with said bar swinging means for moving said pivot relative to said trackway.

35. 32. In a mining machine, a truck movable over a trackway, a self-propelled mining machine of the type normally operative to cut when sliding on its bottom over a mine bottom supported edgewise thereon and secured thereto including a forwardly extending cutter bar, means for driving said truck, means forming a pivot for said bar supported by said truck and located above the latter, and means constantly engaged with the bar for swinging said bar about its pivot in either direction to insert a vertical kerf in an upstanding face which is perpendicular to the line of the trackway, said means being associated with said truck driving means.

50. 33. In a mining machine, a truck movable over a trackway, a self-propelled mining machine disposed edgewise thereon and secured thereto including a forwardly extending cutter bar supported by said truck and located above the latter, a self-contained means constantly cooperating with said bar for swinging the same in opposite directions to insert a vertical kerf in an upstanding face which is perpendicular to the line of the trackway.

60. 34. In a mining machine, a pivoted cutter bar movable in a vertical plane, means for swinging said bar about its pivot positively in either direction including an endless flexible transmission element and means for holding a portion of said flexible element station-

ary during swinging of said bar, and means for adjusting the tension of said element.

35. In a mining machine, a pivoted cutter bar, and means for swinging said bar about its pivot positively in either direction including a plurality of driving members and a flexible element constantly associated therewith, and means for holding one of said members stationary while the other rotates to act on said flexible member.

75 36. In a mining machine, a pivoted cutter bar, and means for swinging said bar about its pivot including a plurality of rotatable members and a flexible element which constantly cooperates with each of said members, and means for holding one of said members stationary and to rotate the other by power.

80 37. In a mining apparatus, a mining machine having a pivoted cutter bar, and means to swing said bar oppositely about its pivot while the latter remains stationary including a plurality of guide rolls swingable with said bar and a flexible member cooperating with said guide rolls in identical reeve during swing in either direction.

85 38. In a mining apparatus, a mining machine having a cutter bar pivoted to swing in a vertical plane, and means for swinging said bar including a plurality of sheaves swingable with said bar and a cooperating endless flexible element.

90 39. In a mining machine, a cutter bar movable in a vertical plane, means for moving said bar including a plurality of rotatable members and a flexible element constantly associated therewith, and frictional means for holding one of said members stationary while the other acts on said flexible element.

100 40. In a mining machine, a pivoted cutter bar, flexible transmission means including a flexible transmission element for swinging said bar about its pivot, said means being operatively connected to said bar at a point offset from its pivot, and friction means independent of said bar swinging means for holding said bar in its different angular positions.

105 41. In a mining machine, a movable cutter bar, means including a flexible member for moving said bar, and means including a brake band for holding said bar in its adjusted position.

110 42. In a mining machine, a movable cutter bar, means for moving said bar in opposite directions including a flexible element, and means associated with said means including a brake band for holding said bar in its adjusted position.

115 43. In a mining machine, a pivoted cutter bar, and means for swinging said bar about its pivot including a plurality of projecting arms carried thereby, a guide sheave rotatably carried by each of said arms for rotation relative thereto, and a flexible member cooperating with said sheaves.

44. In a mining machine, a main frame, a cutter bar pivoted thereon, and means to swing said bar about its pivot including a plurality of angularly disposed guiding members and an endless flexible element cooperating therewith. 5 70
45. In a mining machine, a main frame, a cutter bar pivoted thereon, means to swing said bar about its pivot including a plurality of angularly disposed guiding members and an endless flexible element cooperating therewith, and means to operate said element at different speeds. 10 75
46. In a mining machine, a main frame, a cutter bar pivoted thereon, means to swing said bar about its pivot including a plurality of angularly disposed guiding members and an endless flexible element cooperating therewith, and means to operate said element at different speeds in opposite directions. 15 80
47. In a mining machine, a pivoted cutter bar, and means for swinging said bar including a double strand endless flexible connection, a portion of said flexible connection being stationary during swinging of said bar. 20 85
48. In a mining machine, a driving motor, a feed operating member driven thereby, a pivoted cutter bar, and means to swing said cutter bar about its pivot including an endless double strand flexible element cooperating with said feed operating member and means for holding a portion of said flexible element stationary during bar swing. 25 90
49. In a mining machine, a pivoted cutter bar, means for swinging said bar about its pivot including a plural-strand flexible element, means for holding a portion of said element stationary during bar swing, and means for adjusting the tension of said strands. 30 95
50. In a mining machine, a pivoted cutter bar, and means for swinging said bar about its pivot in opposite directions including a plurality of double strand flexible connections. 45 100
51. In a mining machine, a machine frame, a cutter bar pivotally mounted thereon, and means for swinging said bar including an endless flexible connection, means for holding a point therein stationary, and means for moving another portion thereof. 55 105
52. In a mining machine, a machine frame, a cutter bar pivotally mounted thereon, and means for swinging said bar including an endless flexible connection reeved in a polygon, and means for changing the shape of said polygon to effect swing. 110
53. In a mining machine, a machine frame, a pivoted bar thereon, and means for effecting bar swing including a flexible element cooperating with a fixed point and with said bar at opposite sides of its point of cooperation with said fixed point and a flexible element moving member. 60 115
54. In a mining machine, a machine frame, a pivoted bar thereon, and means for effecting bar swing while its pivot remains stationary including a flexible element cooperating with the bar and with a stationary point, and means cooperating with said element to change the distance between the point of cooperation with the bar and the fixed point. 65 120
55. In a mining apparatus, a machine frame, a pivoted cutter bar thereon, and means for swinging said bar including an endless flexible element cooperatively connected with said bar at spaced points, means for imparting a moving force to the portion of said element at one side of said points, and means for holding said element stationary cooperating with the portion thereof at the other side of said points. 70 125
56. In a mining apparatus, a machine frame, a pivoted cutter bar thereon, and means for swinging said bar including an endless flexible element cooperatively connected with said bar at spaced points, and means cooperating with the portions of said element at each side of said points to effect bar swing. 75 130
57. In a mining apparatus, a truck having running gear, a machine body thereon, cutting mechanism carried by said body including a cutter bar movable relative thereto, and means for driving said running gear and for moving said cutter bar relative to said body including an endless flexible transmission element, said means including separate members directly engaging said flexible element at different points along its length, one of said members constituting a driving member for said running gear and the other member constituting a driving member for moving said cutter bar. 80 135
58. In a mining apparatus, a truck having running gear, a machine body thereon, cutting mechanism carried by said body including a cutter bar movable relative to said body, and means for driving said running gear and for moving said cutter bar relative to said body including a flexible transmission element operatively connected to said cutter bar and said running gear at spaced points along its length, and means for applying power to said flexible element. 85 140
59. In a mining apparatus, a truck having running gear, a machine body thereon, cutting mechanism carried by said body including a cutter bar pivotally mounted thereon for swinging movement in a vertical plane, and means for driving the running gear of said truck and for swinging said cutter bar including a flexible transmission element operative to transmit power to drive the running gear and operatively connected to said cutter bar at a point offset from the bar pivot. 90 145

ing a cutter bar pivotally mounted thereon for swinging movement in a vertical plane, and means for driving the running gear of said truck and for swinging said cutter bar including a flexible transmission element operative to transmit power to drive the running gear and operatively connected to said cutter bar, and means for holding a portion of said flexible element stationary during bar swing.

61. In a mining apparatus, a truck having running gear, a machine body thereon, cutting mechanism carried by said body including a cutter bar pivotally mounted thereon for swinging movement in a vertical plane, and means for driving the running gear of said truck and for swinging said cutter bar including a flexible transmission element operative to transmit power to drive the running gear and operatively connected to said cutter bar at a plurality of spaced points offset from the axis of bar swing.

62. In a mining apparatus, a truck having running gear, a machine body thereon, cutting mechanism carried by said body including a cutter bar pivotally mounted thereon for swinging movement in a vertical plane, and means for driving the running gear of said truck and for swinging said cutter bar including a flexible transmission element, said flexible element constituting the final transmission element through which said bar swinging mechanism is driven and being operative to transmit power to drive the running gear.

63. In a mining apparatus, a truck having running gear, a machine body thereon, cutting mechanism carried by said body including a cutter bar pivotally mounted thereon for swinging movement in a vertical plane, and means for driving the running gear of said truck and for swinging said cutter bar including a flexible transmission element, and means for holding a portion of said flexible element common to both functions stationary while another portion thereof is drawn in to effect bar swing.

64. In a mining machine, a machine frame, a cutter bar pivotally mounted thereon, and means for swinging said bar including an endless flexible transmission connection movable in an orbit, and means for changing the position of said orbit during bar swing.

65. In a mining machine, a machine frame, a cutter bar pivotally mounted thereon for swinging movement in a vertical plane, and means for effecting bar swing including a flexible transmission element cooperating with a fixed point and with said bar at opposite sides of its point of cooperation with the fixed point, and a flexible element moving member.

66. In a mining machine, a machine frame, a pivoted bar thereon, and means for effecting bar swing including an endless flexible

transmission element having double strand connections each cooperating with said bar and at opposite sides of its point of cooperation with a fixed point, and a flexible element moving member.

67. In a mining apparatus, a wheeled truck, a mining machine mounted thereon including cutting mechanism swingable in a vertical plane to cut a plane kerf, and means associated with said truck wheels and said cutting mechanisms for driving the former in opposite directions at different speeds and for swinging the latter during the cutting operation, said swinging mechanism including a final endless flexible transmission element adapted to transmit a direct swinging force to said cutter bar.

68. In a mining machine, a pivoted cutter bar, means for swinging said bar about its pivot in opposite directions including a plurality of double strand flexible connections, and frictional means for holding said cutter bar in its different adjusted positions.

69. In a mining machine, a wheeled truck, a machine body thereon, cutting mechanism carried by said body including a pivoted cutter bar, and means for driving the wheels of said truck and for swinging said cutter bar about its pivot including a plurality of double strand flexible connections.

70. In a mining apparatus, a wheeled truck adapted to run along a trackway, a machine frame on said truck, cutting mechanism on said frame including a cutter bar swingable vertically to cut a vertical kerf, mechanism for driving the wheels of the truck to propel the apparatus along the trackway, and means for swinging said cutter bar during the cutting operation including a final endless flexible transmission element adapted to transmit a direct bar swinging force to said cutter bar.

71. In a mining apparatus, a wheeled truck adapted to run along a trackway, a frame on said truck, cutting mechanism on said frame including a cutter bar swingable vertically to cut a vertical kerf, mechanism for driving the truck wheels to propel the apparatus along the trackway, and means for swinging said cutter bar at a relatively slow cutting speed and a relatively high positioning speed including a final endless flexible transmission element adapted to transmit a direct bar swinging force to said cutter bar.

72. In a mining apparatus, a wheeled truck adapted to run along a trackway, a frame on said truck, cutting mechanism on said frame including a cutter bar swingable vertically to cut a vertical kerf, mechanism for driving the truck wheels to propel the apparatus along the trackway at a slow cutting speed and at a relatively high transport speed, and means for swinging said cutter bar at a relatively slow cutting speed and at a relatively high positioning speed including a final endless flexible transmission element adapted to transmit a direct bar swinging force to said cutter bar.

flexible transmission element adapted to transmit a direct bar swinging force to said cutter bar.

73. In a mining apparatus, a wheeled truck adapted to run along a trackway, a frame on said truck, a motor carried by said frame and having its power shaft horizontally disposed and extending longitudinally of the apparatus, cutting mechanism on said frame including a cutter bar swingable to cut a plane kerf, driving connections between one end of said power shaft and said cutting mechanism, driving connections between the opposite end of said power shaft and the truck wheels for propelling the apparatus along the trackway, and means constantly operatively connected to said bar and driven from the same end of said shaft as said truck wheel driving connections for swinging said bar in opposite directions in a plane path.

74. In a mining apparatus, a wheeled truck adapted to run along a trackway, a frame on said truck, a motor carried by said frame and having its power shaft horizontally disposed and extending longitudinally of the apparatus, cutting mechanism on said frame including a cutter bar swingable to cut a plane kerf, driving connections between the front end of said power shaft and said cutting mechanism, driving connections between the rear end of said power shaft and the truck wheels for propelling the apparatus along the trackway, and means constantly operatively connected to said bar and driven from the rear end of said shaft for swinging said bar in opposite directions in a plane path.

75. In a mining apparatus a wheeled truck adapted to run along a trackway, a frame on said truck, a motor carried by said frame and having its power shaft horizontally disposed and extending longitudinally of the apparatus, cutting mechanism on said frame including a cutter bar swingable vertically to cut a vertical kerf, driving connections between one end of said power shaft and said cutting mechanism, driving connections between the opposite end of said power shaft and the truck wheels for propelling the apparatus along the trackway, and means constantly operatively connected to said bar and driven from the same end of said shaft as said truck wheel driving connections for swinging said bar in opposite directions in a plane path.

76. In a mining apparatus, a wheeled truck adapted to run along a trackway, a frame on said truck, a motor carried by said frame and having its power shaft horizontally disposed and extending longitudinally of the apparatus, cutting mechanism on said frame including a cutter bar vertically swingable to cut a vertical kerf, driving connections between the front end of said power shaft and said cutting mechanism, driving connections between the rear end of said power shaft and

the truck wheels for propelling the apparatus along the trackway, and means constantly operatively connected to said bar and driven from the rear end of said shaft for swinging said bar in opposite directions in a plane path.

77. In a mining apparatus, a wheeled truck adapted to run along a trackway, a frame on said truck, a motor carried by said frame and having its power shaft horizontally disposed and extending longitudinally of the apparatus, cutting mechanism on said frame including a cutter bar swingable to cut a plane kerf, driving connections between one end of said power shaft and said cutting mechanism, driving connections between the opposite end of said power shaft and the truck wheels for propelling the apparatus along the trackway, and means constantly connected to said bar and driven from the same end of said shaft as said truck wheel driving connections for swinging said bar in opposite directions including a final flexible transmission element at all times operatively connected to said bar and constantly operative to effect bar swing in opposite directions.

78. In a mining apparatus, a wheeled truck adapted to run along a trackway, a frame on said truck, a motor carried by said frame and having its power shaft horizontally disposed and extending longitudinally of the apparatus, cutting mechanism on said frame including a cutter bar swingable to cut a plane kerf, driving connections between the front end of said power shaft and said cutting mechanism, driving connections between the rear end of said power shaft and the truck wheels for propelling the apparatus along the trackway, and means constantly connected to said bar and driven from the rear end of said shaft for swinging said bar in opposite directions including a final flexible transmission element at all times operatively connected to said bar and constantly operative to effect bar swing in opposite directions.

79. In a mining apparatus, a wheeled truck adapted to run along a trackway, a frame on said truck, a motor carried by said frame and having its power shaft horizontally disposed and extending longitudinally of the apparatus, cutting mechanism driven from one end of said motor including a pivoted cutter bar, a plural speed transmission mechanism driven from the opposite end of said motor and a rotatable winding member driven thereby, a flexible transmission element operatively connected to said bar at spaced points therein and engaging said winding member at a point therein between said spaced points, said winding member being rotatable through said plural speed transmission mechanism to effect bar swing at different speeds, and mechanism driven from the same end of the motor as said transmission mechanism for driving the truck wheels to propel the apparatus along the trackway.

80. In a mining apparatus, a wheeled truck adapted to run along a trackway, a frame on said truck, a motor carried by said frame and having its power shaft horizontally disposed and extending longitudinally of the apparatus, cutting mechanism driven from the front end of said motor including a pivoted cutter bar, a plural speed transmission mechanism driven from the rear end of said motor and 5 a rotatable winding member driven thereby, a flexible transmission element operatively connected to said bar at spaced points therein and engaging said winding member at a point therein between said spaced points, said 10 winding member being rotatable through said plural speed transmission mechanism to effect bar swing at different speeds, and mechanism driven from the rear end of said motor for driving the truck wheels to propel 15 the apparatus along the trackway.

81. In a mining apparatus, a wheeled truck adapted to run along a trackway, a frame on said truck, cutting mechanism on said frame including a pivoted cutter bar, mechanism 20 for effecting bar swing in opposite directions at different speeds including a rotatable chain sprocket and a flexible chain engaging said sprocket and having its portions at the opposite sides of said sprocket operatively connected to said bar, said chain constituting the 25 final transmission element for transmitting a direct bar swinging force to said cutter bar, and mechanism for propelling the truck along the trackway.

82. In a mining apparatus, a wheeled truck adapted to run along a trackway, a frame on said truck, cutting mechanism on said frame including a pivoted cutter bar, mechanism 30 for effecting bar swing in opposite directions at different speeds including a relatively slow cutting speed in one direction and a relatively high positioning speed in the opposite direction including a rotatable chain sprocket and a flexible chain engaging said sprocket 35 and having its portions extending from said sprocket operatively connected to said bar, said chain constituting the final transmission element for transmitting a direct bar swinging force to said cutter bar, and mechanism 40 for propelling the truck along the trackway.

83. In a mining apparatus, a wheeled truck adapted to run along a trackway, a body on 45 said truck, cutting mechanism mounted on said body including a cutter bar moving member rotatable about a horizontal axis, and mechanism for rotating said member including a final endless flexible transmission element operatively connected to said member to transmit a direct swinging force thereto.

84. In a mining apparatus, a wheeled truck adapted to run along a trackway, a body on 50 said truck, cutting mechanism mounted on said body including a cutter carrying member movable about a horizontal axis, and mechanism for moving said member about its

axis including a rotatable power driven member and a final flexible transmission element 55 engaging said rotatable member and operatively connected to said cutter carrying member, said flexible member being constantly 60 operatively connected to said cutter carrying member and operative to move said member in opposite directions without any change of 65 the relation of said flexible element with respect to said member.

In testimony whereof I affix my signature.

MORRIS P. HOLMES.

CERTIFICATE OF CORRECTION.

Patent No. 1,734,296.

Granted November 5, 1929, to

MORRIS P. HOLMES.

It is hereby certified that error appears in the printed specification of the above numbered patent requiring correction as follows: Page 1, line 52, after the word "mine" insert the word "bottom"; page 4, line 128, claim 16, for the words "positively for" read "for positively"; page 5, line 48, claim 21, for the misspelled word "includinig" read "including", and line 127, claim 28, after the word "plane" insert the word "and"; page 8, line 37, claim 63, for "year" read "gear", and line 45, strike out the words "common to both functions" and insert the same to follow "element" in line 43; page 9, line 37, claim 75, after the word "apparatus" insert a comma; and that the said Letters Patent should be read with these corrections therein that the same may conform to the record of the case in the Patent Office.

Signed and sealed this 13th day of May, A. D. 1930.

(Seal)

**M. J. Moore,
Acting Commissioner of Patents.**
